UNITED STATES PATENT OFFICE

162,243

TREE PROTECTOR

Aldred J. Simmons, Plymouth, Wis.

Application December 2, 1948, Serial No. 149,920

Term of patent 14 years

(Cl. D35—2)

To all whom it may concern:

Be it known that I, Aldred J. Simmons, a citizen of the United States, residing at Plymouth, in the county of Sheboygan and State of Wisconsin, have invented a new, original, and ornamental Design for a Tree Protector, of which the following is a specification, reference being had to the accompanying drawing, forming part thereof, in which

Fig. 1 is a top plan view of a tree protector showing my new design,

Fig. 2 is a perspective view showing the exterior of one half, and

Fig. 3 is a perspective view showing the interior of the same half.

I claim:

The ornamental design for a tree protector, substantially as shown.

ALDRED J. SIMMONS.
